ABSTRACT OF THE DISCLOSURE

A pallet handling machine particularly adapted for use in handling pallets normally used for supporting concrete blocks; said machine comprising a pallet carrying means movable into and out of a position between vertical members of pallet supporting racks and having means wedgeably adapted to pass between a pair of horizontally spaced members of a rack, the pallet carrying means also comprising means to permit said pallet carrying means to move freely laterally of its direction of movement into and out of the racks; said last mentioned means vertically movably operable on a main frame so that the pallet carrying means may successively be moved vertically with respect to a plurality of superimposed shelves in a pallet supporting rack; the said means adapted to be wedgeably engaged between the horizontally spaced members of the racks being adapted to force the pallet carrying means laterally of its movement direction and into alignment with a shelf of the pallet rack.

This invention relates to a pallet handling machine, and more particularly, to a pallet handling machine for handling concrete blocks on pallets immediately after the production of said blocks by a concrete block machine, and during the curing of the blocks, and subsequent thereto at a time when the blocks are ready to be stripped from the pallets.

BACKGROUND OF THE INVENTION

The prior art comprises pallet handling machines which have heretofore been used to receive freshly produced concrete blocks on pallets directly from a production machine, and these pallet handling machines of the prior art have been employed to place laden pallets in racks having superimposed shelves; similar machines have been used to remove the laden pallets from the racks after the concrete blocks have been cured on the pallets.

Due to the lack of uniformity in some of the racks occasioned by accidental rough handling, the racks are not always uniform and therefore the indexing of the racks by means of a suitable support and the advancing of the racks from one bay of shelves to another does not always provide precise alignment of the rack shelves with the pallet handling machine, and consequently, the pallet carrying means of such machines, when moving into position between vertical members of a rack, sometimes interfere with the rack tending to tip the rack over. This has been a serious problem in the operation of automated pallet handling machines when used with pallet

2

supporting racks. Even though the racks may be precisely indexed with relation to the pallet handling machine, uniformity of the racks may vary from time to time due to damage such as bending or the like, as hereinbefore pointed out.

SUMMARY OF THE INVENTION

The present invention employs a very simple and novel means for compensating a pallet handling machine with relation to the actual disposition of horizontally spaced portions of a pallet supporting rack when the pallet carrying means of the pallet handling machine moves into position in the rack to deposit a pallet on a shelf portion of the rack. The present invention utilizes novel compensating means adapted to permit lateral movement of the pallet carrying means in response to a wedgeably operable means connected to the pallet carrying means; said wedgeably operable means adapted wedgeably to be forced between horizontally spaced elements of a pallet supporting rack, and in this manner, the pallet carrying means of the invention slides laterally with respect to its direction of movement while moving into position within a shelf area of a pallet rack.

Specifically, the invention comprises a carriage means vertically movable on a main frame with relation to a plurality of superimposed shelf portions of a pallet rack, and comprises a carriage means movable in a horizontal direction supporting a pallet carrying means and the roller supports for the pallet carrying means are adapted slidably to move longitudinally of their axes in a direction at an angle to the movement direction of the pallet carrying means, and automatically in response to wedging operation of means on the pallet carrying means seeking a position between two horizontally disposed and spaced elements of a pallet supporting rack.

Accordingly, it is an object of the present invention to provide a very simple pallet handling machine which is adapted automatically to compensate for a lack of uniformity of pallet racks which may be inaccurate due to poor construction or damage during handling.

Another object of the invention is to provide a pallet handling machine which automatically prevents many accidents occasioned by pallet carrying means of pallet handlers when moving into shelf positions in pallet racks for depositing laden pallets therein or for removing laden pallets therefrom.

Another object of the invention is to provide very simple and reliable compensating means for pallet handling machine; said compensating means adapted readily and easily to permit movement of a pallet carrying means of the machine in a direction laterally with relation to its direction of movement and to respond in relation to means wedgeably operable between horizontally spaced elements of a pallet supporting rack.

Further objects and advantages of the invention may be apparent from the following specification, appended claims, and the accompanying drawings.

BRIEF DESCRIPTION OF THE DRAWINGS

FIG. 1 is a perspective view of a pallet handling machine showing the machine in relation to pallet supporting racks, and showing only a portion of the machine adapted for loading pallets into the racks;

FIG. 2 is a top or plan view of the machine in FIG. 1, and showing a dual use of the invention wherein the invention is adapted to remove pallets from racks; said pallets carrying cured blocks, and also to load pallets into the racks laden with freshly produced concrete blocks;

FIG. 3 is an enlarged fragmentary sectional view taken from the line 3—3 of FIG. 2;

FIG. 4 is a fragmentary plan sectional view taken from the line 4—4 of FIG. 3, and showing the view rotated substantially 90 degrees from that as shown in FIG. 3;

FIG. 5 is a fragmentary sectional view taken from the line 5—5 of FIG. 3, showing portions of the pallet carrying means and supporting mechanism broken away and in section to amplify the illustration;

FIG. 6 is an enlarged fragmentary sectional view taken from the line 6—6 of FIG. 5;

FIG. 7 is a fragmentary sectional view taken from the line 7—7 of FIG. 6;

FIG. 8 is a view similar to FIG. 3, but showing a modification of the invention;

FIG. 9 is an enlarged fragmentary view similar to FIG. 4, showing the modification as disclosed in FIG. 8;

FIG. 10 is a view taken from the line 10—10 of FIG. 9;

FIG. 11 is a fragmentary view of a modified means of the invention; said means being a wedgeable guide means for the pallet carrying means of the invention adapted wedgeably to move between two horizontally spaced elements of a pallet supporting rack; and

FIG. 12 is a fragmentary sectional view taken from the line 12—12 of FIG. 9, showing by broken lines a varying lateral position of compensating means of the invention adapted to permit lateral automatic movement of the pallet carrying means of the invention in a direction laterally of its normal direction of movement as it passes into and out of a shelf position of a pallet rack.

DESCRIPTION OF THE PREFERRED EMBODIMENTS

As shown in FIGS. 1 and 2 of the drawings, a pallet handling machine, in accordance with the present invention, is disclosed for the purpose of handling pallets relative to pallet racks which support pallets laden with cured blocks and uncured blocks. The machine, as shown, is capable of removing pallets of cured blocks from racks, and also loading the racks subsequently with pallets carrying freshly produced uncured blocks.

In the disclosure of FIG. 1, part of the machine is omitted to permit clarity of the disclosure. The omitted part of the machine is basically similar to the remaining portion of the machine which is disclosed. The omitted part of the machine is the mechanism utilized for removing pallets from racks; said pallets containing cured blocks. This part of the machine is substantially the same mechanism as that disclosed in FIG. 1, which is adapted to load pallets laden with uncured blocks into racks.

In the plan view, as shown in FIG. 2 of the drawings, both portions of the machine which are merely opposite hand structures are shown relative to racks which are movable, and in FIG. 2, the cured block bearing pallets are removable by mechanism of the machine from the racks while pallets laden with uncured blocks are loaded into the racks. Since the mechanism is basically similar, only that portion, as shown in FIG. 1, is disclosed in detail throughout the remaining figures of the drawings.

The machine of the invention comprises a main frame 10 on which a movable frame 12 is vertically movably mounted. The main frame 10 is suspended by a roller chain 14 driven by a sprocket means 16 operable by a reduction gear motor 18. One end 20 of the roller chain is connected to the vertically movable frame while a counterweight 22 is connected to the opposite end of the chain to counterbalance the weight of the vertically movable frame and its component parts.

As shown in FIGS. 3 and 4, the main frame 10 is provided with a pair of vertical track members 24 and 26. These track members 24 and 26 are engaged by rollers 28 on one side and rollers 30 on opposite sides thereof. These rollers 28 and 30 are connected to the movable frame 12 to support it in a vertical movable relation to the main frame 10. It will be seen that the rollers 28 are on one side of the upright members 24 and 26, and that the rollers 30 are on the opposite side thereof at a higher elevation than the rollers 28.

These rollers 28 and 30 are mounted on brackets 32 and 34 of the movable or elevated frame 12.

Mounted on the movable or elevated frame 12 is a carriage frame 36. This carriage frame 36 is provided with rollers 38 operable on an upper side of a track 40 on the elevator frame 12, and rollers 42 on the carriage frame 36 engage a lower track surface of the track 40, as shown in FIG. 5 of the drawings. Thus, the elevator frame 12 moves up and down on the main frame 10 and the carriage frame 36 moves horizontally on the elevator frame 12.

The carriage frame 36 is provided with horizontally disposed pallet carrying platform 44 which is adapted to move into position between horizontally spaced elements 46 and 48 of a pallet rack 50. Secured to a frontal portion of the pallet carrying means 44 is a wedge means having outwardly converging portions 50 adapted to be wedgeably inserted between the horizontally spaced elements 46 and 48 of the rack 50. The pallet carrying means 40 may thus be placed in position to deposit a pallet between the horizontally spaced elements 46 and 48 on a respective shelf of the pallet rack, and shown in FIG. 1, a plurality of vertically spaced shelves designated 52 are provided in each pallet rack bay for receiving or carrying block laden pallets.

In many instances, the racks, as shown in FIG. 1, are provided with uprights 54 which become bent or may lack uniformity in their spaced relation, such that the pallet carrying means 44, as shown in FIG. 4, when moved in a direction of an arrow A between the horizontally spaced elements 46 and 48 may not align properly in which case the wedge means 50 may guide the pallet carrying means 44 between the horizontally spaced elements 46 and 48 and to avoid tipping of the pallet racks 50, the invention is provided with means for permitting lateral freedom of movement of the pallet carrying means 44 so that the wedge means 50 may force the pallet carrying means 44 laterally of the direction in which it moves, while it is moved between the horizontally spaced elements 46 and 48, as shown in FIG. 4 of the drawings.

This means permitting lateral freedom of the pallet carrying means 44 comprises a horizontally disposed track means 54, as shown best in FIGS. 3 and 5 of the drawings. This track means 54 comprises a pair of elongated box-shaped in cross-section tracks 56 which are carried by the elevator frame 12. The pallet carrying platform 44 is coupled to a channel member 58 disposed between the tracks 54 and 56, and secured to opposed portions 60 and 62 of this channel member 58 are pairs of rollers 64 operable in the tracks 56, as shown in detail in FIGS. 6 and 7 of the drawings. The pairs of rollers 54 are spaced apart by a plate 66 which has opposite ends 68 and 70 engaged by a compression spring 72 and 74 contained in the box-shaped tracks 56. A fixed axle 76 passes through each respective portion 60 or 62 of the channel 58 and extends through a pair of rollers 64 and one of the members 66, all as shown best in FIGS. 6 and 7 of the drawings. Thus, the springs 72 and 74 being in opposed relation to each other tend to hold the member 66 and each pair of rollers 64 in a centered position normally to hold the pallet carrying platform 44 in a normally centered relation with respect to the horizontally spaced portions 46 and 48 of each pallet rack. However, 75 when these members are displaced either by lack of posi-

tioning control or due to the fact that they may have been bent, the wedge means 52 forces the pallet carrying means 44 laterally, such that the rollers 64 move in the tracks 56 against compression of one of the springs 72 or 74 in the respective direction as urged by engagement of one of the converging portions 52 of the wedge means with one of the horizontally spaced portions 46 or 48 of the pallet rack 50. Thus, it will be seen that the combination of the wedge means and the means on the carriage frame 36 to permit lateral freedom of movement of the pallet carrying means 44 provides for automatic alignment of the pallet carrying means 44 with a respective rack shelf area to deposit a block laden pallet therein or for the purpose of entering the rack to remove a block laden pallet, as the case may be.

It will be understood that the horizontally spaced portions 46 and 48 may be angle iron members forming shelf portions 52 or they may be vertical elements of the frame of each pallet rack, if desired. In FIG. 1, the pallet carrying means of the invention may be aligned with a conveyor 80 extending from a concrete block producing machine, this conveyor being adapted to carry pallets 82 laden with blocks 84, and the pallet carrying platform 44 is adapted to support the respective pallets and blocks, and thus deposit the laden pallets in the pallet racks 50, as hereinbefore described.

As shown in FIG. 2 of the drawings, the conveyor 80 is parallel to another conveyor 86 which moves away from the racks 50, and the conveyor 86 is aligned with a pallet carrying platform similar to the platform 44, but adapted to remove laden pallets from the racks, as the rack is moved in the direction of an arrow B in FIG. 3 of the drawings. The racks containing pallets loaded with cured blocks are carried away by the unit designated 88 which is similar and opposite hand to the unit designated 90 and containing the hereinbefore described main frame, elevator frame, and carriage frame of the invention. Thus, the unit 88, as shown in FIG. 2, removes pallets laden with cured blocks to expose shelves in the racks as they move in the direction of the arrow B to the unit 90 which loads the racks with uncured blocks from the conveyor 80 which receives them from a production machine.

It will be appreciated that the invention relates to a pallet handling machine where it loads or unloads laden pallets from racks, and particularly the invention relates to means for aligning the pallet carrying means of the invention with the rack shelves without creating undue lateral pressure on the racks which may tend to upset them or deflect them.

In the modification of the invention as shown in FIGS. 9 to 12, inclusive, the uprights 24 and 26 of the main frame are engaged by rollers 28 and 30 which support brackets 100 and 102 of a modified elevator frame 104 of the invention. Mounted on this elevator frame 104 are horizontally disposed channel-shaped tracks 106 and 108. These tracks are opposed and their open sides, as shown in FIG. 12, are directed toward each other.

A carriage frame 110 is provided with rollers 112 and 114 disposed in said tracks, and the lateral spacing of these rollers is such that they may slide longitudinally of the axes in accordance with the direction of the arrows C and D in FIG. 12 of the drawings, to permit the carriage frame 110 to move laterally and to permit the pallet carrying platform of the modified structure of the invention, designated 116, to move laterally in the directions of the arrows C and D.

Secured to the pallet carrying platform 116 on the horizontally movable carriage frame 104 is a wedge means 120 having converging portions 122 operating similarly to the hereinbefore described wedge portions 52. This operation being with respect to the horizontally spaced portions 46 and 48 of the hereinbefore described pallet rack 50.

When the converging portions 122 are forced between the horizontally spaced portions 46 and 48 of the pallet rack 50, and when slight misalignment occurs, the pallet

carrying platform 116 is moved laterally in the direction of either of the arrows C or D, as the case may be, forcing the rollers 112 and 114 to slide laterally or longitudinally of their axis and laterally in the tracks 106 and 108.

5 A pair of plate springs 124 and 126 tend to maintain the carriage frame 110 in an intermediate position with relation to the tracks 106 and 108 so that the pallet carrying platform 116 may normally be aligned in a median position.

10 The carriage frame 110, as shown in FIG. 9 of the drawings, is driven back and forth by an endless belt 130 driven by a gear reduction motor 132. A similar arrangement may be seen in FIG. 3, wherein a belt 134 is coupled to the carriage frame 12 to move it back and 15 forth or carrying the pallet carrying means or pallet carrying platform into and out of position between the upright members or horizontally spaced members of the pallet racks.

As shown in FIG. 9 of the drawings, the carriage frame 116 is provided with clip arms 138 clipped to the endless belt 130 so that as it is rotated in one direction, the carriage frame is extended, and when rotated in another direction, the carriage is retracted.

According to a further modification of the invention, as shown in FIG. 11, the wedge means is modified by providing a pair of rollers 140 and 142 which tend to provide opposed converging surfaces adapted wedgeably to be forced between the horizontally spaced members 44 and 48 of the pallet racks 50. These rollers 140 and 142 are mounted on the pallet carrying platform 116 in a similar manner to the wedge means 120 with its converging portions 122, as shown in FIGS. 9 and 10 of the drawings. Thus, the invention comprises generally a combination wherein a carriage frame is adapted to carry a pallet carrying means and is provided with means for allowing lateral freedom of movement of the pallet carrying means laterally with respect to its movable direction, and wherein means is connected with the pallet carrying means, and adapted wedgeably to be forced between a pair of horizontally spaced members of a pallet rack so as to compensate for misalignment and to force the pallet carrying means to move laterally of its direction of movement in order to align with shelf areas of the pallet racks.

45 It will be obvious to those skilled in the art that various modifications of the present invention may be restored to in a manner limited only by a just interpretation of the following claims.

I claim:

1. In a pallet handling machine, the combination of: a main frame; and elevator frame movable up and down on said main frame; a carriage frame movable back and forth along a rectilinear axis and in a horizontal direction on said elevator frame; a pallet holding rack adjacent said carriage frame; said pallet holding rack having a pair of portions spaced apart in a horizontal direction; said carriage having guide means adapted wedgeably to be forced between said pair of portions to guide said carriage into position with respect to said rack for depositing a pallet therein; pallet carrying means on said carriage and coupled to said guide means; and compensating means supporting said pallet carrying means for movement laterally with respect to said rectilinear axis of said carriage, said compensating means adapted to permit said pallet carrying means to respond in a direction laterally with respect to said rectilinear axis, when said guide means is wedgeably engaged with one of said pair of portions on said rack.

60 2. The invention, as defined in claim 1, wherein: said compensating means includes elongated track means disposed in parallel relation to said rectilinear axis; and rollers supporting said pallet carrying means, said rollers slideable in an axial direction generally laterally relative to said track means and said pallet carrying means.

65 3. The invention, as defined in claim 2, wherein: said

track means includes a pair of opposed channel-shaped members open in a horizontal direction toward each other, said rollers slidable therein longitudinally with respect to their rotary axes.

4. The invention, as defined in claim 1, wherein: said compensating means comprises a track means on said carriage and supporting said pallet carrying means, said track means being elongated in a direction at an angle to said rectilinear axis of said carriage, said pallet carrying means thus movable in said last mentioned direction with respect to said rectilinear axis.

5. The invention, as defined in claim 1, wherein; said compensating means includes elongated track means disposed in parallel relation to said rectilinear axis, said track means supporting said carriage on said elevator

frame; and rollers engaged on said track means and supporting said pallet carrying means, said rollers slidable in an axial direction generally laterally relative to said track means and laterally with respect to the direction of movement of said pallet carrying means.
